Fig. 3

Fig. 5

FIG. 1 is a perspective view of a game box showing my new design.

FIG. 2 is a plan view of the game box.

FIG. 3 is a bottom view of the game box.

FIG. 4 is a side elevational view; and

FIG. 5 is an end elevational view.

This application is a continuation of D. 20,623, filed Dec. 29, 1969, abandoned, a continuation of D. 16,181, filed Mar. 11, 1969, abandoned.

I claim:

The ornamental design for a game box, substantially as shown and described.
